STAMPING PRESS FOR ROTATABLE ARTICLES

John Muller, Waldwick, N. J., assignor to Peerless Roll Leaf Co., Inc., Union City, N. J., a corporation of New York

Application May 4, 1939, Serial No. 271,722

11 Claims. (Cl. 41—7)

This invention relates to stamping presses, and particularly to stamping presses adapted to operate upon articles capable of being rolled along the bed of the press during the impressing thereof. Therefore embodiments of the invention may be termed "rotary" stamping presses.

In the stamping of articles which are capable of being rolled along a supporting surface—as, for instance, cylindrical pencils—with gold leaf, or other transfer medium, it has heretofore been difficult to obtain a clean cut impression over more than a limited area of the circumferential surface of the article.

It is a primary object, therefore, of this invention to provide a method of, and a stamping press for, impressing a transfer medium on a circumferential surface so that the resulting impression will be clean cut and the transfer medium will be substantially uniformly distributed.

An object is to provide a stamping press for the purpose, that will be capable of economical manufacture and efficient operation.

An object is to provide for the effective control of a supply of transfer medium in strip form to the impression zone of the press so that waste will be reduced to a minimum.

In accomplishing the objects of the invention, an outstanding feature of the method resides in the carrying out of the impressing operation while the article is being rolled along a supporting surface. The impressing die is, advantageously, made to initiate and motivate the rolling action of the article during the impressing operation.

An important feature of the stamping press resides in the provision of a substantially vertical stamping bed against which the article to be stamped is pressed during the impressing operation, and in the provision of yieldable supporting means for controlling the rolling descent of the article during the impressing operation.

An important feature resides in the provision of a mechanism, having a limited upward stroke, for withdrawing excess portions of the transfer medium strip from the impression zone of the press following each impressing operation.

Further objects and features of the invention will be apparent from the following detailed description.

In the drawings:

Fig. 1 represents a side elevation of a preferred embodiment of stamping press pursuant to the invention with operating parts shown as they appear at an initial stage of the impressing operation.

Fig. 2 represents an enlarged fragmentary view, in top plan, of the die holder and die holder mounting;

Fig. 3 represents a vertical section taken along the line 3—3 of Fig. 1;

Fig. 4 represents an enlarged vertical section taken along the line 4—4, Fig. 1;

Fig. 5 is a fragmentary view illustrating the top portion of Fig. 1 with operating parts as they appear at an advanced stage of the impressing operation;

Fig. 6 is a view corresponding to Fig. 5 but illustrating operating parts as they appear at the completion of the down stroke of the die and die holder;

Fig. 7 is a diagrammatic representation in vertical section of the impressing operation in its initial and final stages; and

Fig. 8 is a view corresponding to Fig. 7, but illustrating the position of the elements at the commencement of the next succeeding impressing operation.

The embodiment of stamping press illustrated is a preferred construction, manually operable. It is adapted for removable attachment to a suitable supporting structure.

In Fig. 1, a bracket frame element 10 is shown removably anchored to a supporting structure 11 by means of bolts 12, 12 passing through the anchor plate portion 10a of the bracket frame element 10.

The bracket arm portion 10b of the bracket frame element 10 is angularly configurated, see Fig. 3, for structural strength, and serves to support, at its outer extremity, on a lateral extension 10c, see Fig. 4, an upwardly extending standard 13, secured thereto by means of the bolts 14, 14.

The top of the standard 13 is rabbeted, and a slideway 15 is formed by the addition of a removable edge strip 16, secured to standard 13 by means of screw 17.

Disposed for reciprocative adjustment relative to the slideway 15 is a stamping bed and mounting which comprises a slide portion 18, configurated to fit and slide within the slideway 15, an apertured lug 18a, depending from the outer end of the slide 18, and a stamping bed 19, extending from the other end of the slide 18, and having preferably a plane, substantially vertically disposed, bed surface. The slide portion 18 may be inserted into and removed from the slideway 15 by placement and removal of the edge strip 16.

For adjusting the position of the stamping bed 19 with respect to the die and die holder mecha-

nism (to be hereinafter described), a thumb-screw 20 is journaled within the aperture of depending lug 18a. It has a threaded shank extending into threaded engagement with the female threaded bore 21, which passes through standard 13, and a knurled head for manual manipulation.

The die and die holder, the latter being either a die plate or a chase, are mounted for reciprocation in a plane substantially parallel with and spaced apart from the bed surface of the stamping bed 19. For this purpose, a standard 22, having the foot portions 22a, 22a extending from opposite sides thereof at its base, is mounted 15 upon and rises upwardly from the anchor plate 10a. The bolts 12, 12 advantageously pass through the foot portions 22a, 22a for securing the standard 22 as well as the bracket frame element 10 to the supporting structure 11.

20 The front face of standard 22 is grooved, see 23, Fig. 2, along its height, and a slide piece 24a of a slide 24, which carries a die holder mounting 25, is slidably received thereby. Guideway retaining strips 26, 26 are secured to the front face 25 of standard 22 and extend over the marginal edges of the slideway 23 to form tracks which are received by grooves 27, 27 formed laterally of the slide piece 24a. The limit of the upstroke of the slide 24 and of its carried mechanism is determined by the limit stop finger 28a of the limit stop pieces 28, the latter being secured to the top of standard 22 as by means of screws 29, 29. A rabbet groove 30 is advantageously formed at the top of slideway piece 24a for cooperation with the limit stop finger 28a.

30 The slide 24 and its carried die holder mounting 25 are adapted to reciprocate vertically along the front face of standard 22. For effecting the reciprocation, a rack 31 has its upper end formed 40 as a tongue 31a which is received by a yoke 24b, see Fig. 3, depending from the lower end of die holder mounting 25. A pin 32, see Fig. 1, passed through the yoke and tongue, serves to articulatively secure rack 31 to die holder mounting 25. 45 A pin 32, see Fig. 1, passed through the yoke and tongue, serves to articulatively secure rack 31 to die holder mounting 25. An aperture 10-1 extending through the bracket arm 10a provides 50 passage for the rack 31 in its reciprocative movement.

55 A frame element 33 depends below bracket frame element 10 and has an angled upper end 33a secured to the bracket arm 10b by means of the screw 34. A manually manipulatable crank 35 is slidably mounted on the frame element 33, intermediate the upper and lower ends thereof. A pinion 36 is rigidly secured to the rotatable shaft portion 35a of the crank 35. The rack 31 extends down below crank 35 and is held in 60 meshing engagement with pinion 36 by means of the protruding end of a pin 37. The pin 37 extends through the frame element 33 and projects on the other side thereof to form a post for anchoring the upper end of a coil spring 38. A pin 39 is secured to the lower end of rack 31 and projects through a slot 40 which extends diagonally at the lower portion of frame element 33. The pin 39 projects from the frame element, as does pin 37, to form a post for anchoring the lower 65 end of coil spring 38.

70 Accordingly, when crank 35 is manually manipulated clockwise, rack 31 is lowered, and die holder mounting 25 is correspondingly lowered, along the front face of standard 22. Pin 37 serves 75 to keep rack 31 in engagement with pinion 36.

and slot 40 accommodates the pin 39 as the rack moves downwardly. During the downstroke, coil spring 38 is tensioned, and, if crank 35 is released at the termination of the downstroke, rack 31 is immediately elevated through the upstroke, automatically, by the return action of tensioned spring 38.

5 75 Mounted on the die holder mounting 25 is a die holder, being, in the illustrated instance, a chase 41, and carried by the chase 41 is a die 42. The chase 41 is secured in place by means of top and bottom clamping pieces 43, 43 which cooperate with wedge-shaped protuberances 41a, 41a at the base of the chase. The screws 44, 44 secure the wedge pieces 43, 43 to the die holder mounting 25 as well as securing the die holder mounting 25 to the slide 24.

20 Since the instant embodiment of stamping press is intended to be utilized for impressing a transfer medium, such as metallic gold leaf, mounted on a suitable backing strip by a heat releasable medium, the chase 41 is made suitably heat conducting, and a heating element 45, see particularly Figs. 1 and 2, is firmly secured within the die holder mounting 25. The heating element 45 is preferably electrically energized, and, for this purpose, an electric cord 46 connects therewith. The slack of the electric cord 46 may be supported by a hanger element 47, Fig. 1.

30 The transfer medium and backing is preferably 35 in strip form, see 48, rolled as at 49, and is fed in controlled amounts to the impression zone of the press. A roll 50 carries the roll 49 of strip transfer medium, and is removably mounted for rotation on a stub shaft 51, against an adjustable 40 collar 52. As is customary, a friction brake is provided as a guard against undue ease of unreeling. For this purpose a coil spring 53 is interposed between the reel 50 and a second adjustable collar 54, it being operative to yieldably press reel 50 against collar 52.

45 The stub shaft 51 is rigidly secured to the upper end of a frame element 55 which is, in turn, secured to standard 22 by means of short shaft connections 56 and 57.

50 For aiding in the control of feed of the transfer medium strip 48 to the impression zone of the press, a counterweighted lever 58 is fulcrumed on a short shaft 59 which extends rigidly from frame element 55. The counterweight 60 is articulatively mounted on one end of the lever 58, for adjustment longitudinally thereof, by means of a thumb screw 61. A short shaft 62 extends rigidly from the other end of the lever 58 into the path 55 of feed of transfer medium strip 48. The spaced guides 62a, 62a, define, therebetween, a cylindrical bearing surface for the support of the transfer medium strip 48 in its travel.

65 The stamping press is primarily adapted to impress rollable articles with a transfer medium, 60 the impression being made while the article is rolled along the bed of the press. This method of impressing a cylindrical article with a transfer medium has been found to be most practical for obtaining a clean-cut impression and even distribution of the transfer medium, and the only practical way of impressing, at one operation, around the full periphery of the article.

70 Accordingly, the effective surface of the stamping bed 19 is preferably plane. In the present instance it extends vertically, in direct opposition to the reciprocative path of travel of the chase 41 and die 42. Its mounting on adjustable slide 18 affords placement relative to die 42 in accordance with the thickness of the article to be impressed. 75

The article to be impressed may, for example, be a cylindrical pencil as indicated at 63, Fig. 1. For maintaining the article in solid contact with the impression surface of the bed 19 during its travel in the impression zone of the press, a pair of resilient strips 64, 64, respectively, advantageously of spring metal, are spaced apart a distance slightly greater than the width of the die 42 and extend substantially vertically at opposite sides thereof. They have angled upper ends, which are fastened, as by means of the screws 65, 65, to an angled bracket 66, secured in any convenient manner, as by screws, to the upper portion of the slide 24. The resilient strips 64, 64, thus press against the article 63 during the entire downstroke of the die and die holder.

For yieldably supporting the article 63 during the descent of die 42 and during the actual impression operation, a supporting roller 67 is rotatably mounted between the upper ends of the spaced upstanding fingers 68, 68, the fingers, in turn, being rotatably mounted at their lower ends on opposite ends of a shaft 69. Shaft 69 is rigidly mounted between the forward ends of the levers 70 and 71, which are fulcrumed intermediate their forward and rearward ends by means of the pin 72 extending through and projecting on both sides of the standard 22. The rearward end of lever 70 is rigidly connected to lever 71 by means of a pin 73. The lever 71 extends rearwardly a greater distance than does lever 70, and has articulatively mounted on its rearward end, for adjustment horizontally thereof, as by means of the thumbscrew 74, a counterweight 75.

The upstanding fingers 68, 68 have lateral extensions 68a, 68a in each of which a slot is formed for the reception of a set screw 76. The set screws 76, 76 hold the upstanding fingers 68, 68 rigidly in suitably adjusted position relative to the space between the impression surface of the stamping bed 19 and the resilient strips 64, 64 for the proper support of article 63. The upper limit of the stroke of levers 70 and 71 is determined by a set screw 77 which is threadedly carried by the angled bracket piece 78.

As the die and die holder descend through their down stroke and roll article 63 downwardly by reason of frictional impression abutment of the die 42 against the surface of the article, the forward ends of the counterweighted levers 71 are forced downwardly, the article 63 rolling freely of roller 67.

55 The counterweight 75 may be adjusted relative to the lever arm 71 as found necessary for a given article to be impressed, the size and weight of the article being determinative factors.

The transfer medium strip 48 is led downwardly from the short shaft 62 through the impression zone of the press over roller 67 and between the spaced guides 69a, 69a of shaft 69. The article to be impressed, see the article 63, may be manually, or otherwise, inserted into the space between the stamping bed 19 and the resilient strips 64, 64, preferably by rolling thereto from the top. Thus, the article will rest on a partial loop of the transfer medium strip 48, the partial loop being held against the article by the resilient strips 64, 64 and the roller 67, and the partial loop conforming to the curved surface of the article by reason of the weight of the waste carrier strip 48—1. It is assumed, of course, that the strip 48 is fed into the impression zone of the press with its transfer medium

facing forwardly so as to be in direct contact with the surface of the articles to be impressed during the impression operation. The waste carrier strip 48—1, or, if the marking medium is in strip form per se without a backing strip, the waste portion of the marking medium passes downwardly through an aperture 10—2 which extends through bracket arm 10b at an appropriate position below the impression zone of the press.

10 The impressing operation is initiated and carried to completion by manually turning the crank 35 in a clockwise direction until the lower limit of the downward stroke is reached. Thereupon, the crank may be released and the rack 31 15 allowed to move upwardly by reason of the return force exerted by the tensioned coil spring 38. During such upstroke, of course, crank 35 rotates freely.

20 For determining the lower limit of the downward stroke of the die and die holder, an arm 79 is pivoted, at its upper end, outwardly from the die holder mounting 25, as indicated at 80, and hangs pendulous therefrom. A pin 81 extends from the lower end of arm 79 in such manner as to contact the sloping upper edge of lever 70, and to ride downwardly therealong during the downstroke of the die and die holder. When the pin 81 contacts the particular upstanding finger 68 concerned, see Fig. 6, the die holder 30 mounting 25, and, thus, the die and die holder, is prevented from further downward movement. It will be noted, however, that at this stage, the impression operation has been accomplished and the duly impressed article has rolled free of 35 the supporting roller 67 into the receiving pocket formation 82, provided by the bracket arm 10b of the frame element 10. Because of this limiting relationship, violent rebound of the supporting roller 67, under the influence of the counterweight 75, is prevented. Pin 81 serves as a check on the rise of roller 67 during the upstroke of the die and die holder.

40 The feed of the transfer medium strip 48 to the impression zone of the press during the impression operation is automatically controlled, according to requirements, by the cooperative impression relationship between the die 42 and the article being impressed. As indicated diagrammatically in Fig. 7, the die 42 has a cameo 45 impression surface which is pressed into the yielding surface of the article, the transfer strip 48, of course, being interposed between the impression surface of the die and the surface of the article. Thus, as the article is rolled downwardly, during the impression operation, from the position indicated in full lines in Fig. 7 to the position indicated in dotted lines, the transfer medium strip 48 is pulled downwardly, and, thus, is unreeled from its roll 49 by a length corresponding to the distance of the descent.

55 The length of the transfer medium strip 48 unreeled is greater than the length actually utilized. This oversupply actually fed is not wasted, however, for, during the upward stroke of the die 65 and die holder, after the duly impressed article has rolled clear of the impression zone of the press, the counterweighted lever 58 carries the short shaft 62—over which the strip 48 is guided—upwardly, and thus carries the strip 48 upwardly 70 to place it in proper position for the next impression operation.

For providing an adjustment for the determination of the extent to which the transfer medium strip 48 is withdrawn from the impression zone of 75

- the press in the compensating for the over-supply actually fed during the impression operation, an arm 83 has a split end 83a adjustably clamped, as by means of the screw 84, about the stub shaft 59.
- 5 A pin 85 extends from the other end of the arm 83 in such manner as to function as a limit stop controlling the extent of upward movement of the forward lever arm portion of the counterweighted lever 58. Thus, the upward stroke of the short 10 shaft 62—over which the transfer medium strip 48 is guided—may be limited as is found proper in the particular instance. In Fig. 8 is diagrammatically illustrated the proper position of the transfer medium strip for a succeeding impression 15 operation.

- The die holder, as indicated at 41—1, Fig. 1, may be arranged for the reception of a plurality of dies similar to the die 42 or of a larger die than the die 42.
- 20 For the stamping of articles of molded plastic material pursuant to the method disclosed in the copending application of Arthur M. Wickwire, Jr. and John Müller, Serial No. 255,905, filed February 11, 1939, and entitled Method of impressing, 25 suitable means may be provided for heating the article to be impressed.

For the stamping of tapered or otherwise irregularly configurated rollable articles, the stamping bed and the die holder may be swiveled, or otherwise articulatively mounted.

30 While this invention has been illustrated and described with respect to only one preferred embodiment thereof, it should be clearly understood that many changes may be made without departing from the generic scope of the invention as set forth herein and in the claims that follow.

I claim:

1. In a stamping press, a stamping bed having a bed surface disposed substantially vertically, an 40 impressing die spaced apart from the said bed surface and mounted for reciprocation along a path substantially parallel thereto, means for reciprocating said impressing die along said path, means for supplying a transfer medium in strip form between the article to be stamped and said impressing die, and means for withdrawing a limited length of the said strip of transfer medium from the impression zone of the press following each impressing operation.

50 2. In a stamping press, a stamping bed having a bed surface disposed substantially vertically, an impressing die spaced apart from the said bed surface and mounted for reciprocation along a path substantially parallel thereto, means for reciprocating said impressing die along said path, means for supplying a transfer medium in strip form between the article to be stamped and said impressing die, means for yieldably supporting the article to be impressed during the impressing operation, and means for withdrawing a limited length of said strip of transfer medium from the impression zone of the press following each impressing operation.

60 3. In a stamping press, a stamping bed having a bed surface disposed substantially vertically, an impressing die spaced apart from the said bed surface and mounted for reciprocation along a path substantially parallel thereto, means for reciprocating said impressing die along said path, 70 means for supplying a transfer medium in strip form between the article to be stamped and said impressing die, resilient means for urging the article to be impressed into contact with said bed surface during the impressing operation, supporting means disposed between said bed surface and

said resilient means for supporting the article to be impressed during the impressing operation, said supporting means being mounted for yieldable displacement downwardly during the impressing operation and for automatic return following each impressing operation, and means for withdrawing a limited length of the said strip of transfer medium from the impression zone of the press following each impressing operation.

4. In a stamping press, a stamping bed having a bed surface disposed substantially vertically, an impressing die spaced apart from the said bed surface and mounted for reciprocation along a path substantially parallel thereto, means for reciprocating said impressing die along said path, means for supplying a transfer medium in strip form between the article to be stamped and said impressing die, supporting means disposed between said bed surface and said resilient means for supporting the article to be impressed during the impressing operation, said supporting means being mounted for yieldable displacement downwardly during the impressing operation and for automatic return following each impressing operation, means for withdrawing a limited length of the said strip of transfer medium from the impression zone of the press following each impressing operation, and limit stop means controlled by the movement of said impressing die for determining the lower limit of the said displacement of said supporting means.

5. In a stamping press, a stamping bed having a bed surface disposed substantially vertically, an impressing die spaced apart from the said bed surface and mounted for reciprocation along a path substantially parallel thereto, means for reciprocating said impressing die along said path, means for supplying a transfer medium in strip form between the article to be stamped and said impressing die, roller supporting means disposed between said bed surface and said resilient means for supporting the article to be impressed during the impressing operation, said roller supporting means being mounted for yieldable displacement downwardly during the impressing operation and for automatic return following each impressing operation, and means for withdrawing a limited length of the said strip of transfer medium from the impression zone of the press following each impressing operation.

6. In a stamping press, a stamping bed having a bed surface disposed substantially vertically, an impressing die spaced apart from the said bed surface and mounted for reciprocation along a path substantially parallel thereto, means for reciprocating said impressing die along said path, means for supplying a transfer medium in strip form between the article to be stamped and said impressing die, supporting means disposed between said bed surface and said impressing die for supporting the article to be impressed during the impressing operation, said supporting means being mounted for yieldable displacement downwardly during the impressing operation and for automatic return following each impressing operation, means for withdrawing a limited length of the said strip of transfer medium from the impression zone of the press following each impressing operation, limit stop means controlled by the movement of said impressing die for determining the lower limit of the said displacement of said supporting means, said limit stop means being so constructed and arranged as to prevent the said supporting means from rising

more rapidly than does the said impressing die during its upstroke.

7. In a stamping press, a stamping bed having a bed surface disposed substantially vertically, said stamping bed being mounted for adjustment in substantially a horizontal plane, an impressing die spaced apart from the said bed surface, a mounting for said impressing die, said mounting being arranged for reciprocation along a path substantially parallel with said bed surface, means for reciprocating said mounting along said path, means for supplying a transfer medium in strip form to the impression zone of the press, means for controlling the feed of said strip of transfer medium to the impression zone of the press and for withdrawing a limited length of the said strip of transfer medium from the said impression zone following each impressing operation, resilient means for urging the article to be impressed against said bed surface, supporting finger means carried by counterweighted lever means, said supporting finger means rising upwardly between the said bed surface, and the reciprocative path of said impressing die for supporting the article to be impressed, said supporting fingers and said counterweighted lever means being so arranged that, during an impressing operation, the downward movement of the article being impressed will depress the said supporting finger means, and that the said supporting finger means will return to its original supporting position, stop means determining the original supporting position of said supporting finger means, a pendulous arm carried by said mounting for the impressing die, contact means carried by the pendulant end of said pendulous arm, said contact means being arranged to slide along the said counterweighted lever means during the downstroke of said impressing die mounting and to abut against said supporting finger means to define the termination of the downstroke of said impressing die mounting, said supporting finger means being adjustable relative to its said counterweighted lever means, and the counterweight of said counterweighted lever means being adjustable.

8. In a stamping press, a stamping bed having a bed surface disposed substantially vertically, said stamping bed being mounted for adjustment in substantially a horizontal plane, an impressing die spaced apart from the said bed surface and mounted for reciprocation along a path substantially parallel thereto, means for reciprocating said impressing die along said path, means for supporting the article to be impressed against said bed surface, oscillating means for guiding and controlling the feed of a transfer medium in strip form to the impression zone of the press, and means for limiting the oscillatory stroke of said oscillating means.

9. In a stamping press, a stamping bed having a bed surface disposed substantially vertically, said stamping bed being mounted for adjustment in substantially a horizontal plane, an impressing die spaced apart from the said bed surface and mounted for reciprocation along a path substantially parallel thereto, means for reciprocating said impressing die along said path, means for supporting the article to be impressed against said bed surface, said means being adjustably

yieldable to afford rolling of said article downwardly along said bed surface, and being arranged to return to original position following an impressing operation, oscillating means for guiding and controlling the feed of a transfer medium in strip form to the impression zone of the press, and means for limiting the oscillatory stroke of said oscillating means.

10. In a stamping press, a stamping bed having a bed surface disposed substantially vertically, said stamping bed being mounted for adjustment in substantially a horizontal plane, an impressing die spaced apart from the said bed surface and mounted for reciprocation along a path substantially parallel thereto, means for reciprocating said impressing die along said path, means for supporting the article to be impressed against said bed surface, counterweighted lever means having guide means mounted at its free end portion for controlling the passage of a transfer medium in strip form to the impression zone of the press, and limit stop means limiting the upward stroke of said free end portion of said counterweighted lever means.

11. In a stamping press, a stamping bed having a bed surface disposed substantially vertically, said stamping bed being mounted for adjustment in substantially a horizontal plane, an impressing die spaced apart from the said bed surface, a mounting for said impressing die, said mounting being arranged for reciprocation along a path substantially parallel with said bed surface, means for reciprocating said mounting along said path, means for feeding a transfer medium in strip form into the impression zone of the press, counterweighted lever means having guide means mounted at its free end portion for controlling the passage of a transfer medium in strip form to the impression zone of the press, adjustable limit stop means limiting the upward stroke of said free end portion of said counterweighted lever means, resilient means for urging the article to be impressed against said bed surface, supporting finger means carried by counterweighted lever means, said supporting finger means rising upwardly between the said bed surface and the reciprocative path of said impressing die for supporting the article to be impressed, said supporting fingers and said counterweighted lever means being so arranged that, during an impressing operation, the downward movement of the article being impressed will depress the said supporting fingers, and that the said supporting finger means will return to its original supporting position, stop means determining the original supporting position of said supporting finger means, a pendulous arm carried by said mounting for the impressing die, contact means carried by the pendulant end of said pendulous arm, said contact means being arranged to slide along the said counterweighted lever means during the downstroke of said impressing die mounting, said supporting finger means being adjustable relative to its said counterweighted lever means, and the counterweight of said counterweighted lever means being adjustable.

12. In a stamping press, a stamping bed having a bed surface disposed substantially vertically, said stamping bed being mounted for adjustment in substantially a horizontal plane, an impressing die spaced apart from the said bed surface and mounted for reciprocation along a path substantially parallel thereto, means for reciprocating said impressing die along said path, means for supporting the article to be impressed against said bed surface, oscillating means for guiding and controlling the feed of a transfer medium in strip form to the impression zone of the press, and means for limiting the oscillatory stroke of said oscillating means.
